UNITED STATES PATENT OFFICE.

EDWIN E. OVERHOLT, OF WASHINGTON, DISTRICT OF COLUMBIA,
ASSIGNOR TO THE OVERHOLT RAILWAY SIGNAL COMPANY, OF
CHICAGO, ILLINOIS.

SAFETY DEVICE FOR DISPLAY OF TRAIN-ORDER SIGNALS.

SPECIFICATION forming part of Letters Patent No. 683,861, dated October 1, 1901.

Application filed March 22, 1901. Serial No. 52,386. (No model.)

To all whom it may concern:

Be it known that I, EDWIN E. OVERHOLT, a citizen of the United States, residing at Washington, in the District of Columbia, have 5 invented certain new and useful Improvements in Safety Devices for the Display of Train-Order Signals; and I do hereby declare the following to be a full, clear, and exact description of the invention, such as will enable others skilled in the art to which it app- 10 pertains to make and use the same.

My invention relates to devices for the prompt and proper display of signals in railroading, and is equally adapted to either of 15 the two systems of signaling now in common use—namely, that in which the signal stands normally “clear” and that in which it stands normally at “danger” when orders are received for a train.

20 For the benefit of those not acquainted with railroading let it be said that when we speak of the signal being set “red,” which is synonymous with being set at “danger,” we mean that the train-order signal, which is 25 usually painted red, has been brought into a horizontal position, pointing across the railroad-track, as illustrated in Fig. 15, and that when it is set “clear” or “white” it is in a dependent position, with the end of the signal 30 next the railroad-track pointing downward to the ground.

My object is to provide means adapted to coöperate with railroad signals or semaphores in such a way that it will be impossible for 35 an operator to receive an order for a train without displaying the danger-signal, even though he be careless or in a stupor from overwork or loss of sleep. Hence it will appear that a device of the character herein 40 shown will be of great value, especially on single-track railroads, where there is constantly more or less danger of head-end collisions, which danger to life and property may be practically averted by the use of my 45 invention, as herein set forth.

A further object is to divide the responsibility of having the proper signal displayed among three parties—the train-despatcher, the operator, and the conductor or the en- 50 gineman for whose train the orders are in-

tended—and this is done in such a way that if an accident should occur the faulty party could at once be detected.

Another very important object in view has been the practical one of obtaining these re- 55 sults by means purely mechanical—means so simple and of so few parts that there shall be nothing to easily wear out or get out of order, and withal that may be manufactured and installed at a minimum cost without fur- 60 ther cost for maintaining.

These practical considerations render the employment of electricity for this and kindred purposes very undesirable, as such appliances are necessarily complicated, having 65 many parts, are costly and difficult to manufacture, are expensive to maintain, and easy to get out of order, besides requiring an expert for their most successful operation.

It is in contradistinction to means employing 70 electricity particularly that I have used the terms “means mechanical” and “mechanical means,” in the specification and claims of this application.

To fully appreciate the operation and construction of my invention, as well as its adaptability to the work to be done, it must be borne in mind that in the requirements necessary to its operation it conforms to certain arbitrary rules in common use among all 75 railroad companies, and that it compels the punctual and faithful observance of these rules with possible slight additions under some circumstances. These rules are substantially as follows—namely, all railroad 80 companies have specially-prepared blanks upon which operators are required to receive train-orders. In receiving orders for a train the operator is required to take a number of manifolds or carbon copies of the same, and 85 in no case less than two—one for the conductor and one for the engineman on the train for which the orders are intended—in addition to the copy which he keeps. As soon as 90 orders are received for a train the operator is required to repeat the same to the despatcher in order that he may see that it has been received correctly, and, if so, the operator must at once set the train-order signal “red,” which indicates that he has received 95 100

orders for a train, or "danger." When the expected train arrives, the conductor and engineman are each given a copy of the orders received, which copies must be signed by the 5 operator. In like manner the conductor must sign the copy, which the operator keeps as evidence that he (the operator) has discharged his duty faithfully. In order that all copies of an order may be alike in every 10 respect—position on the page and all—it is required that they be made before the slips of paper on which they are written are detached from the tablet, and it is obligatory on conductors not to sign or in any other way 15 recognize orders that have been detached from the tablets.

Briefly stated, the principles of the construction and operation of my invention are as follows: It consists, primarily, of a box 20 or cabinet containing blank train-order tablets normally locked therein. This cabinet also contains a bar with which the signal is operated and which at the same time it is operating the signal is coöperating with the 25 door of the cabinet in such a way as to lock and unlock it. The operator is compelled not only to put all his train-order tablets into the cabinet, but also to lock them in every 30 time he sets his signal "clear" for a train to proceed, since the bar which operates the signal cannot be moved till the door is closed, and when moved in the direction to set the signal "clear" it locks the door in this closed position, so that when the operator needs a 35 tablet upon which to receive the next order he is compelled to move the operating-bar in the proper direction to unlock the cabinet containing the tablets, and this movement of the operating-bar again displays the danger- 40 signal.

In order that the operator shall be compelled, as stated above, to replace all the tablets in the cabinet before he can give the operating-bar the proper movement to set the 45 signal "clear," the cabinet is provided with a series of locks equal to the number of tablets it is adapted to carry, one lock for each tablet, each of said locks being operated independently of the others by its own individual 50 tablet. These locks coöperate with the operating-bar in such a way that when one of the tablets is removed its lock engages said bar and will not permit it to be moved to "clear" the signal till the tablet-lock has 55 been disengaged, which can only be done by replacing the tablet in the cabinet.

For any who may desire it I have further provided means whereby when the signal has been set at "danger" it cannot be changed 60 till the conductor of the incoming train arrives and coöperates with the operator in setting the signal "clear."

Again, I have provided means whereby a watchman's time-recorder may be used in 65 connection with the signal-operating mechanism to indicate, if need be, the exact time at which the signal is set—in every instance

either "red" or "white." In connection with the signal-operating mechanism I have also provided means whereby an alarm will be 70 given every time a train attempts to pass a danger-signal without heeding it.

Having thus briefly set forth the principles and operation of my invention, I now proceed to more specifically and fully describe the 75 same and the means whereby these results are accomplished, reference being had to the accompanying drawings, forming a part of this application, and in which—

Figure 1 is a perspective view of the cabinet containing the blank tablets upon which train-orders are to be received. Fig. 2 is a perspective view of the cabinet with its top and lid or door removed. Fig. 3 is a view of the lid or door of the cabinet. Fig. 4 is a perspective view of the tablet-locks as they appear related to each other in their operative position. Fig. 5 is a perspective, on a larger scale, of one of these locks removed from the group to which it belongs. Fig. 6 illustrates 80 a central vertical section of the cabinet. Fig. 7 is a similar view showing slight modifications and additions. Fig. 8 is a view in perspective of the operating-bar. Fig. 9 is a perspective view of the inner top section of the 85 cabinet. Fig. 10 is a perspective of the locking-plate of the operating-bar. Figs. 11, 12, and 13 illustrate different forms of tablets that may be used. Fig. 14 is a sectional view of the form of cabinet illustrated in Fig. 7, 90 having the operating-bar thrust inward and one of the tablets partially withdrawn, said bar also being shown in coöperation with a watchman's time-recorder. Fig. 15 shows a semaphore provided with means for sounding 95 an alarm when the danger-signal is unheeded. Fig. 16 illustrates a slightly-modified form of the same. Fig. 17 shows a modified form of the alarm-lever illustrated in Fig. 15. Fig. 18 is a perspective of the alarm-lever of 100 Fig. 16.

For convenience of reference I have indicated the various parts of my invention by numerals, the same numerals referring to the same parts throughout the various figures of 115 the drawings.

Referring to the drawings, the numeral 1 indicates the case or cabinet, provided with the horizontal shelves or tablet-supports 2 and having the vertically-moving lid or door 3, the operating-bar 4, and the series of tablet-locks 5. The shelves 2 have sufficient space between them to easily receive a blank tablet for train-orders. In Figs. 1 and 2 the spaces intervening between the shelves are 120 exactly equal to the thickness of the shelves. The door 3, made, preferably, of metal, is provided with a series of alternating cut-away and uncut-away portions corresponding in 125 number and in width to the shelves and intervening spaces of the cabinet and designed to coöperate therewith to open and close the cabinet.

The front edges of the right and left sides

of the cabinet extend forward slightly in front of the shelves, and each of these forward extensions is provided on its inner face with a vertical groove 6, and into these grooves the door 3 is snugly received, so that it may freely move up and down therein.

When the uncut-away portions of the door forming the fingers 7 are brought into position to overlap the spaces 2^a, intervening between the shelves, the door is said to be closed, as access to the spaces 2^a is thereby cut off, and when the cut-away portions of the door are in registration with the spaces intervening between the shelves of the cabinet the door is said to be open, as all the spaces are then accessible.

The shelves 2 are provided with the recesses 8, centrally located on the front edge thereof, and the central portion of the door 20 is also removed, forming an opening which coincides with these recesses and permits the tablets to be easily grasped.

Centrally located in the front and rear sides of the cabinet and near the bottom thereof are the rectangular apertures 9, adapted to movably receive the operating-bar 4, and in the bottom of the door 3 is the opening 10, through which the said operating-bar 4 extends outwardly when the door is in its operative position. Extending downwardly from the upper side of this opening 10 of the door is the lug 11. Between the lower end of this lug and the lower side of the opening 10 there is just sufficient space to easily receive the operating-bar 4, and it will be seen that when this space is brought into position to receive the said operating-bar, as in Fig. 1, the door is in its closed position, and, further, that when the operating-bar is in the position shown in that figure the door can be moved neither upward nor downward, but is locked in that position by the bar, and that even though the top of the cabinet should be removed the door could not thereby be moved in a way to gain access to any of the tablets. If the lower part of the door were removed and the opening 10, which at first sight seems unnecessary, were thereby done away with, leaving the lug 11 extending downwardly from the bottom of the door, then by removing the top of the cabinet the door could be removed and access had to all the tablets without changing the position of the operating-bar, and hence without moving the signal; but the object of providing the opening 10, through which the operating-bar 4 must pass, is to prevent that possibility.

The operating-bar 4 is provided with the aperture 12, adapted to coöperate with the lug 11 of the door, and when it is desired to unlock the door all that is necessary is to move the operating-bar forward till the said aperture 12 is brought into position to receive the lug 11, which permits the door to drop downwardly by gravity a sufficient distance to open the cabinet, as already explained, and renders all the tablets accessible.

The forward end of the operating-bar 4 carries the bolt 13, engaging the rod 14, Figs. 1, 15, and 16, by which the signal is operated; and it is apparent from the construction shown that the forward movement of the operating-bar necessary to the unlocking of the door of the cabinet will move the operating-rod 14 of the signal in a direction to set the signal at "danger," as it appears in Figs. 15 and 16. Hence we see that the very act of unlocking the cabinet to get a blank upon which to receive a train-order sets the signal "red," so that it can never be said of an operator that from weariness or overwork he forgot, or even neglected, to display the proper signal, for the system and mechanism employed compel him to display it before an order is received, and the only way not to display the signal is not to receive the order at all, in which case the despatcher holds the train, it being an established rule that a train shall never be permitted to proceed beyond certain points till orders have been received for that train at certain other points ahead; and it is evident that where my invention is in use if an order be received and wired back to the despatcher he knows that the proper signal is displayed at the point to which the order was sent.

The operating-bar 4 has the recess 15. (Clearly illustrated in Fig. 8.) This recess is surrounded by the plate 16, Figs. 8 and 10, and is so located that when the bar is thrust forward sufficiently to bring the lug 11 of the door into coöperation with the recess 12 of said bar the said recess 15 will be in registration with the series of tablet-locks, with which locks it is designed to coöperate. These tablet-locks are clearly illustrated in perspective in Figs. 4 and 5 and are loosely supported in a vertical position in the rear part of the cabinet, their upper and lower ends being received, respectively, into the apertures of the plates 18 and 19, the former of which is carried by the top shelf of the cabinet, Fig. 2, being countersunk therein, and the latter is attached to the under side of the lower shelf very close to the operating-bar 4, the reason of which will be pointed out hereinafter. Partly for the sake of economizing space the central front portion of these locks is deeply cut away. Each, however, is provided at a certain point in its length with an uncut-away portion 20, which forms a forwardly-extending lug or projection which has its lower edge inclined. These tablet-locks correspond in number to the number of shelves in the cabinet—one for each shelf—and their forward projections 20 are so located that the lower or inclined face of some one of these projections is normally substantially opposite each one of the intervening spaces between the shelves of the cabinet, so that when a tablet is thrust into one of these intervening spaces its front edge will come into contact with the inclined face of the projection 20 of one of the locks and will elevate

the lock sufficiently to lift it out of contact with the operating-bar and will support it in that position, Fig. 7. Of course the tendency of these locks is to drop downwardly 5 by gravity till they rest upon the bar 4; but they cannot thus drop down till the tablets are moved out of their normal position, and this cannot take place till the operating-bar has been moved forward to that point 10 which permits the door to become unlocked by gravity, which movement of the bar 4, as already specified, sets the signal "red" and brings the recess 15 of the bar immediately beneath the series of tablet-locks. It then 15 follows that whenever a tablet is withdrawn the lock which it controls will drop downwardly into the said recess 15, as shown in Fig. 14, where the operating-bar is thrust inward, the door unlocked, and one of the tablets 20 partially withdrawn. Hence it happens that whenever one or more of the tablets are withdrawn the operating-bar is thereby locked in the position which holds the danger-signal displayed; nor is there any way of with- 25 drawing the bar, and thereby changing the signal, till all the tablets have been restored to their normal position in the cabinet, and not only must they be restored to their position in the cabinet, but the cabinet must be 30 locked upon them before the operating-bar can be moved outwardly to change the signal, for it is apparent that when the tablets are all in their normal position in the cabinet and their locks all elevated out of contact 35 with the operating-bar the bar is still locked in the position it occupies till the door is moved upwardly a sufficient distance to dis-engage its lug 11 from the recess 12 of the said bar 4, which upward movement of the 40 door locks the tablets in the cabinet as it unlocks and frees the bar. When the bar has thus been freed, but not till then, can it be drawn inwardly as a means of changing the signal from "danger" to "clear." The movement 45 of the bar is properly limited by the stop 21, which is rigidly attached at the proper point to the under side of said bar. The plate 19, as already stated, is located very close to the operating-bar, the object of this being to give 50 to the locks the greatest possible power of resistance without liability to become twisted or warped by any unusual strain imposed upon them—as, for instance, by a sudden jerk of the operating-bar—in order to set the 55 signal "clear" when the operator has forgotten to replace one or more of the tablets in the cabinet.

The reason why the operator is not only compelled to replace all the tablets in the 60 cabinet every time he sets the signal "clear," but also to lock them in, is that next time a train-order is given and he wants a blank upon which to receive the same he will be compelled to operate his box in order to obtain 65 said blank, and this operation insures that the danger-signal shall again be displayed.

The tablets used in this device may be made

in the usual way—that is, attached to a base-piece or back of ordinary pasteboard—but preferably with this difference, that the base-piece shall be longer than the tablet, so that it will extend beyond it either to the front or rear, as illustrated in Figs. 11 and 13, or in both directions, as shown in Fig. 12. The tablet is attached to the base-piece in the ordinary way by causing the two to adhere together by the application of glue to a greater or less portion of their adjacent surfaces or in any preferred way. The projecting portions 22^a of the tablets are utilized to operate 80 the tablet-locks, as may be clearly seen from Figs. 6, 7, and 14, for while the tablets without this projecting portion could be made to reliably operate the locks it could not be done with so great an economy of space, as a 85 greater and constantly-varying distance of movement of the locks would have to be provided for, due to the greater and constantly-varying thickness of the tablets, and there are other reasons why this arrangement is 90 better, one of which is that only a very slight and uniform movement of the locks has to be provided for. It will be noticed that these projections extend sufficiently beyond the tablet to prevent the tablet-blanks from coming 95 in contact with the lugs 20, by which their edges might be marred or torn.

In the tablet illustrated in Fig. 11, with the base-piece projecting in front, if the tablet should be suddenly thrust into its place in 100 the cabinet there would be danger of the air getting between the leaves and raising the upper ones, so that they would probably contact with the under side of the shelf immediately above and would get turned back 105 and rumpled as the tablet moved inwardly. Carelessness in entering the tablet into the recess provided for it might produce the same result, especially if through handling the corners should have been turned up a little, 110 as illustrated. Hence it is thought that in practice the form illustrated in Fig. 13, with the base-piece extending to the rear of the tablet, will be the best. This, however, is a matter to be determined by experience and 115 by the preferences of the users.

With the base-piece extending in both directions, as shown in Fig. 12, either the front or the rear edge of the tablet may be first entered in the cabinet, as shall best suit the 120 pleasure or convenience of the operator.

The tablet-locks may be made of any preferred material; but it is thought that metal will be best for that purpose. Aluminium, on account of its lightness, might be found useful here, as the locks if made of this material would still be sufficiently heavy to drop down promptly by gravity and engage the bar 4 whenever a tablet was removed. These locks made of ordinary strap-iron give 125 entire satisfaction, as has been proved by actual test, and it is also found that ordinary or even light pasteboard base-pieces used with the tablets are all that is necessary to un-

failingly operate the locks. It will be observed from Fig. 9, as well as in the sectional views of the cabinet, that there is a recessed portion 23 in the center of the rear edges of 5 the shelves, and it will be seen that the forwardly-projecting lugs 20 of the locks extend into these recesses, so that that portion of the base-piece of the tablets which contacts with the lugs and elevates the locks is supported by 10 the upper edges of the walls of these recesses. By this means that portion of the base-piece of the tablets which contacts with the locks is so well supported that it may be made of comparatively light material; but supposing 15 the recess 23 to be dispensed with and the path of the locks to be entirely in the rear of the shelves, even then ordinary pasteboard base-pieces would answer every requirement. No two of the lugs of the tablet-locks lie in 20 the same vertical plane. Hence it is apparent that every time a tablet is replaced in a different shelf from the one it was removed from a different point on the base-piece thereof comes in contact with the lug of the 25 tablet-lock. Hence the very slight wear that takes place on the edge of the base-piece of the tablet is not all at one point.

Inasmuch as it is contrary to the rules of all railroads for a train to leave a station till the 30 train-order signal is set "clear," it follows that of necessity the conductor and engineer of each train that has been stopped by a train-order signal become interested parties in certain operations of the box whenever 35 they are delayed by the failure of the operator to properly display the white signal. Their own personal safety also makes them vitally interested in seeing that the operator performs his duty faithfully in displaying 40 the danger-signal, and my device herein set forth makes it easy for them to detect any neglect upon his part, as in that case it becomes an infallible witness against him. If, however, on the other hand, he has been faithful 45 in the discharge of his duty and has displayed the proper signal and they fail to regard it, the apparatus then becomes a faithful witness against them, all of which will be pointed out more fully hereinafter.

50 It has already been shown that the forward movement of the operating-bar 4 necessary to lower the door as a means of unlocking the cabinet permits the bar to be locked in its forward position by means of the downwardly-extending lug 11 entering the recess 12 of the bar and that every time a tablet is removed from the cabinet the bar is additionally locked in this position by one of the tablet-locks dropping into the recess 15 of the 55 bar. In addition to these safeguards I have further provided for any who may desire it a third lock for the operating-bar, which lock engages the bar whenever the signal is set at "danger" and renders it absolutely impossible to change it to "clear" till a train has arrived bringing a conductor or engineman, who must cooperate with the operator in or-

der to change the signal. This lock 24 is illustrated in Figs. 7 and 14 and is located on the inner side of the back of the cabinet immediately above the operating-bar. The locking-plate 16 of the bar 4 is provided at its inner end with the recess 25. (Clearly illustrated in Figs. 8 and 10.) This recess is so located with reference to the lock 24, which is preferably a spring-lock, that when the bar 4 is moved into position for the lug 11 of the door to engage the recess 12 of the said bar the lock 24 will simultaneously therewith engage the recess 25, as shown in Fig. 14. 80 Now I propose that only conductors and enginemen shall be given keys to this lock. Hence the necessity that one or the other of them coöperate with the operator in moving the bar to change the signal. Access is had 85 to this lock through the keyhole 26.

In order to guard against accidents in case some of the signal-operating mechanism should get broken, it is customary to so construct signals that their tendency is to stand 90 at "danger." This is usually effected by making the rear end 27, Figs. 15 and 16, of the signal very heavy in comparison with the front portion or blade 28 thereof, which is usually made thin and light. Hence the signals 95 always tend to assume the position shown in Figs. 15 and 16, and being connected with the operating-bar 4, as set forth in this application, it follows that when the signal is set at "clear" the bar will receive a tendency 100 from the signal to move inwardly. Hence in the case of roads having their signals standing normally "clear" it is necessary to provide means such that when the bar is withdrawn to set the signal "clear" it may be 105 conveniently and securely held in that position, and to provide for this without adding any additional parts to my device I have utilized the lug 11 of the door for this purpose, as will be seen by referring to Fig. 7, in which 110 case I have provided the protecting-plate 16, Fig. 10, of the operating-bar 4, Fig. 8, with the recess 29, and this recess is so located with reference to the stop 21 on the under side of the operating-bar that when the bar 115 is withdrawn to its full limit (as it must be to set the signal "clear") the recess 26 will be brought into registration with the aforesaid lug 11, which will drop down into it by gravity, and thereby lock the bar in that position. Hence it appears that the lug 11 of the door coöperates with the bar 4 to lock it, and through it the signal, in whichever position it is caused to assume. It goes without saying that all that is necessary in either case 125 in order to remove this lock is to elevate the door, which can easily be done by placing the forefinger on top of the cabinet at the front edge thereof and bringing the thumb under the top bar of the door or under the thumb-piece 3^a attached thereto and lifting it upward.

In Figs. 1, 2, and 6 the thickness of the shelves and the width of the intervening

spaces are equal, except in so far as the thickness of the shade lines effect the showing intended, and the width of the fingers 7 of the doors in those figures is the same as the width 5 of the shelves and spaces with which the said fingers coöperate, so that when the door is at its downward limit the spaces are entirely uncovered and the edges of the shelves are entirely covered, and vice versa. This provides 10 for the shortest possible vertical movement of the door to entirely open and close the intervening spaces of the cabinet; but in Figs. 7 and 14 the arrangement shown requires that the door move the same distance 15 as in the other case plus the depth of the recess 29 of the protecting-plate 16 of the guide-bar 4, Figs. 8 and 10, and that this may be accomplished and yet have the intervening spaces between the shelves of the cabinet entirely 20 closed when its lug 11 is brought into engagement with the recess 29 I have made the thickness of the shelves equal to that of the other shelves plus the depth of the recess 29, and from the width of the intervening spaces 25 is subtracted the space added to the shelves. The fingers of the door are the same width as in the other case. By this arrangement the spaces intervening between the shelves of the cabinet are entirely closed when the signal is 30 set at "clear," and when thus closed, as in Fig. 7, the fingers 7 of the door overlap the lower side of the intervening spaces a distance equal to the depth of the recess 29; but while the bar is in the process of being withdrawn 35 into the position just indicated the intervening spaces are also closed, but with the fingers of the door overlapping them the same distance at their top edges.

From what has been said about the tendency 40 of the signal to pull the bar 4 inwardly it might be more accurate in speaking of the movement of this bar to say that we permit the bar to move inwardly. However, it is only a matter of expediency as to which way 45 the bar shall be arranged to move in order to set the signal in a given position. It might be arranged just as well for it to move outwardly in order to display the danger-signal as to move inwardly, as shown. However, 50 if the danger-signal is to be displayed the greater portion of the time it is then better for the bar to be thrust inward for that purpose, as in that position only the handle of the bar projects in front of the box to be in 55 the way of the operator, for it is thought that the best place to locate the cabinet will usually be on the operator's table, rigidly secured thereto near his telegraph instruments.

In case an operator should be wilfully perverse and should so far disobey the rules as to take a train-order on ordinary paper or on another tablet or on anything whatsoever than one of the tablets withdrawn from the 60 cabinet after he had been called to the telegraph instrument to receive the order I provide the means illustrated in Fig. 14, where-

by he may be detected. Of course we are providing against a condition that cannot arise from stupor occasioned by overwork or loss of sleep, or from stupidity, or even from carelessness or inefficiency, but from pure, wilful, premeditated perversity, such as getting a tablet by theft or cunning or by removing one from the cabinet and replacing it with something else, &c. It goes without saying that an operator could only make his task more difficult by not using his box; but the danger arises from the fact that if he should receive an order without operating his box, 70 and thereby setting his signal "red," he might forget to set his signal and a collision might ensue, or if so perverse he might intentionally leave the signal "clear" in order to wreck a train, only being careful to set the signal "red" after the train had passed in order to make it appear to those who came to investigate that he had done his duty by displaying the proper signal, and thereby 75 put the blame of the wreck on an innocent conductor or engineman. To infallibly detect any such evil attempt upon the part of an operator, I provide means whereby some part of the signal-operating mechanism shall coöperate with a watchman's time-recorder 80 in such way that there will be a record made every time the signal is operated. In the present instance I have preferred to locate the time-recorder 30 on the wall 31 of the operator's office just above the operating-bar 4. 85 The time-recorder is suitably protected by the housing or casing 32, which is provided on its front side with the transparent door 33, through which the face of the recorder may be viewed. Only conductors or other 90 designated parties are provided with means for opening the housing 32 and gaining access to the time-recorder within. The operating-bar 4 enters the housing 32 through an aperture 34 in the lower front side thereof. 95 This bar carries an angle or bracket 35, which comes in contact with the recording-pin 36 of the time-recorder when the bar is thrust inward to unlock the cabinet and makes a record of the time the act takes place. 100

As the watchman's time-recorder is not a part of my present invention, but only an accessory thereto, its parts are only slightly illustrated, as it is thought that all the reference necessary thereto can be made by specification. 105

The inward movement of the pin 36 is resisted by a spring which causes it to promptly move outward whenever the bar 4 is withdrawn. The inner end of this pin 36 is bent 110 upwardly and trips the trigger of the time-recorder by both its inward and its outward movement, so that it makes a record both coming and going, and that without in any way interfering with the rotation of the dial 115 of the recorder, however long the signal may be left in one position or the other. Hence it is apparent that the recorder will show just 120 how often the bar was moved inward or out-

ward and will also show the exact time at which each movement was made, and if an operator from evil intent should fail to display the danger-signal till after the train had passed the time-recorder would indicate that fact when investigation was made. This showing could only be prevented by breaking the recorder, which would of itself be sufficient evidence of guilt; but, besides this, let it be borne in mind that when a train despatcher gives an operator a train-order the operator is required to repeat the order to the despatcher, so that he may verify it. The despatcher not only keeps a copy of the order, but opposite it on his order-book notes the time at which it was verified.

It has already been stated that when an operator receives an order he is required to take at least two manifold copies of the same—one for the conductor and one for the engineer of the train for which the order is given—and that he must require the conductor to sign the copy which he keeps for his (the operator's) own use and for inspection. Now if it be required of the conductor that whenever he signs his name to the operator's copy to also write opposite his signature the time at which that order was received, as indicated by the time-recorder, it becomes apparent that any failure upon the part of the operator to operate his box at the time he receives orders may be readily discovered when these signed orders are inspected, since the time they were received, as gathered from the time-recorder and noted opposite the signature of the conductor, will not correspond to the time the order was verified, as shown by the despatcher's record-book, or the conductor may at stated intervals remove the records from the time-recorder and send them to the party who inspects the orders. By comparing these records with the orders sent in for inspection, or with the despatcher's order-book, an operator's record for a long period may be easily reviewed. Hence an unfaithful man may be quickly and easily detected and an inspector may know as perfectly how faithful or unfaithful his operators have been in displaying their signals as if he had been standing by each one the entire time. Moreover, if a conductor suspects any unfaithfulness when he notes the record of the time-recorder he may as soon as he chooses communicate with the proper official about the same, and if he deems the case urgent this may be done by wire.

In Figs. 15 and 16 I have illustrated means of safety entirely different from the watchman's time-recorder shown in Fig. 14, and yet in some respects it answers the same general purpose—as, for instance, it would bear strong testimony against an operator who had failed to display a danger-signal till after the train to be stopped had passed. It also possesses additional features designed to promote safety. As already stated, the signal herein illustrated normally tends to as-

sume the danger position, as illustrated in Figs. 15 and 16. The signal-pole carries the signal-actuating lever 38, pivoted thereto by 70 the pivot-bolt 39. At the lower end of the signal-lever 38 is the aperture 40, the other end of said bar being connected to the operating-bar 4 of the cabinet by means of the bolt 13, located in the forward end thereof. 75

It has already been specified that when the operating-bar 4 of the cabinet has been moved inwardly to unlock the door the signal will have been caused by that movement to assume the danger position, as in Figs. 15 and 80 16. In this position the signal-lever 38 and the rod 41, connecting it with the signal, have moved downwardly from the position partially shown in dotted lines. The signal-lever 38 carries at a suitable point the pivot 85 42, which loosely engages the slot 43, located in the upper end of the bell-rod 44, the lower end of which rod is pivotally connected to the inner end of the bell-lever 45. At a suitable point in its extent this lever 45 has the upward extension 46, at the upper end of which it is pivoted to the post 47, while the outward and slightly-upturned end 48 thereof stands immediately by the railroad-track and is slightly elevated above the top surface of one 90 of the rails 49. Located on the signal-post 37, at any suitable height, is the bell or gong 50, having the ringing-lever 51. The bell-rod 44 carries the adjustable bracket 52, suitably located with reference to the ringing-lever 51. 100 Now it is apparent from the construction shown that when the signal is in this position, indicating "danger," and a train passes over the rails 49 the upturned end 48 of the alarm-lever will be forced downwardly, and it is 105 further apparent that by this movement, which occurs every time a wheel passes over the end 48 of the bell-lever 45, the rod 44 will be elevated vertically, and that the bracket 52 will contact with the ringing-lever 110 51 and cause the bell to ring. The slot 43 at the upper end of the bar 44 permits the bar to move up and down freely without imposing any strain upon the signal-lever 38. The utility of providing the alarm-lever 45 with 115 means whereby its fulcrum-point may be located above the plane occupied by the lever itself is apparent from the following considerations, namely: It is necessary that the upturned end 48 of the alarm-lever 45 should 120 be very close to the side of the rail in order that the wheels of the locomotive and cars may overreach and depress it when the signal is set at "danger." Of course this could be accomplished with the fulcrum in the same 125 plane occupied by the lever; but in that case if a stone or a piece of material of any kind were to get between the said upturned end 48 of the lever and the rail the lever would be liable to get wedged fast and would then fail 130 to operate, or if the track got spread the same objectionable results would follow, or, again, the effects of freezing or of expansion by heat might cause binding between the parts men-

tioned. With the present arrangement when the end 48 of the lever is depressed it swings slightly from the rail, so that there can be no binding between these two parts. In practice it will probably be convenient for the end 48 of the lever to abut against the rail, so that the rail may constitute a stop therefor, as illustrated in Fig. 17, and it is apparent that the lever as there illustrated will readily adapt itself to any spreading of the track or to any changes that may be produced by heat, cold, &c., and that while doing this it will always remain abutting against the track in a position to be depressed by the wheels of a passing train whenever the signal is standing at "danger." When the signal is set "clear," the end 48 of the lever 45 will be lowered to a plane below the top of the rail, so that a passing train will not ring the bell. Moreover, if the upwardly-extending stem 46 of the lever 45 extend upwardly very far, as illustrated in Fig. 17, the lever 45 will have sufficient horizontal motion imparted to it, when the signal is set "clear," to withdraw the end 48 beyond the reach of the overlapping part of the car-wheels.

Referring to Fig. 15, it will be seen that when the lever 38 is moved upwardly toward the position shown in dotted lines to set the signal "clear" the rod 44 will move upwardly with it a sufficient distance to ring the bell 50, which if the signal-pole be some distance from the operator's office, as is often the case, will serve to notify the operator that the signaling mechanism, &c., is in working order. When the rod 44 descends, as the signal is set to "danger," the bracket 52 descending with it will permit the ringing-lever 51 to descend, and thereby ring the bell again to notify the operator that the signaling mechanism is intact and that the alarm is set.

If the signal-pole is very near the operator's office, and it should for any reason not be desired to have the bell ring every time a signal is set, the slightly-modified form of bell-ringing means illustrated in Fig. 16 may be employed. In this figure the signal-operating lever is substantially like the corresponding lever 38 of Fig. 15. Its signal-operating rod 54 corresponds to the rod 41 of that figure. It is provided with the pivot 55, corresponding to the pivot 39 of that figure, and the bell-rod 56 has a slot 57, which loosely receives the pivot 55 just as the pivot 42 receives the slot 43 of the rod 44. The upper end of the bell-rod 56 is held in position by the eye-bolt 58, while its lower end passes downwardly through the slot 59, Fig. 18, of the bell-lever 60. The lower end of this bell-rod 56 is provided with two nuts 61 and 62, separated a short distance from each other, and the portion of the rod lying between these two nuts is engaged by the slot 59 of the lever 60. The outer end 63 of the bell-lever 60 is sufficiently heavy to overbalance the other end of the said lever, and thereby impart to it an upward tendency, which keeps it in contact with the

under side of the nut 61. When the signal is set at "danger," as shown, the upturned end of the alarm-lever will extend above the face of the rail 65, and if an engineer should fail to see the signal and should pass on rapidly over the track the sudden depression which the wheels of his train would give to the upturned end 64 of the lever 60 would cause its inner end to thrust the bell-rod 56 upwardly with such momentum as to uniformly ring the bells.

To prevent the bell-rod 56 from moving upwardly too far, and thereby imposing a strain on the ringing-levers and possibly jarring the signal-operating mechanism also, I provide the stop-block 66, made of yielding material and suitably located immediately above the upper end of said rod. Now if the double bracket 67, adjustably secured to the bell-rod 56, be moved up to a point sufficiently near to the bell-ringing levers 68, lying in the vertical path of said bracket, the bells 69 will be rung every time a signal is changed, just as in the case of the bell 50 in Fig. 15; but the said double bracket 67 may be located on the rod 56 at a point sufficiently below the ringing-levers 68 of the bells as not to come in contact with them when the rod 56 is moved upwardly in the act of setting the signal "clear." Hence it is a matter of choice with the operator as to whether the bell shall give a ring every time a signal is set. When the rod 56 is moved upwardly, the weighted end of the alarm-lever 60, pivoted to the post 70, will be permitted to move downwardly by gravity sufficiently to bring the upturned end 64 of said lever below the path of the overlapping edges of the wheels of a train, so that no alarm will be rung when the signal is set "clear."

In the alarm mechanism illustrated in Fig. 16 I have employed two bells, and the object thereof is not only to produce a greater volume of sound, but I also propose that the bells shall differ in tone one from the other, so that the alarm given shall be all the more marked and noticeable. If found desirable, the internal mechanism of the bells may be such that they will not both strike simultaneously in ringing, but will alternate with each other. It is thought that it will be best to locate these bells opposite the cab-window, so that they will be more apt to attract the engineer in case they sound an alarm.

It is a matter of expediency and convenience as to whether the signal-operating levers 38 and 53 shall be located high up on the pole, as in Fig. 15, or near to the ground, as in Fig. 16.

From the construction of the alarm appliances connected with the signals it is apparent that if for any reason a train should run by one of these signals when set at "danger" not only the conductor and trainmen would hear the alarm, but everybody on the train, and if the bells have a strikingly noticeable sound, as already mentioned, the traveling

public would soon come to recognize the significance of this alarm. It will further appear that if an operator should fail to display the danger-signal for a train till after 5 the train had passed not only the conductor and trainmen would be witnesses against him, but everybody on the train could testify that no alarm was heard, and that therefore he had not yet set the signal at "danger" at 10 the time the train passed, however nicely he might have arranged it afterward to shield himself from blame.

The above description refers to my invention as applied more particularly to single-track roads, where there is but one signal used at a station. The method of adapting it to meet the requirements of double-track roads, where two signals are used at each station, and also the method of permitting trains 20 to pass for which there are no orders while there are orders on hand for other trains and that without returning any of the tablets to the cabinet, will be set forth in a succeeding application.

25 Having thus fully described the principles of my invention and shown means whereby these principles may be applied to use, I yet do not wish to be limited to the exact showing made, but desire protection on all that 30 comes clearly within the spirit and scope of my invention.

What I claim as new, and desire protection upon by Letters Patent, is—

1. In safety devices for displaying train-order signals, a case containing train-order blanks normally inaccessible therein; means coöperating therewith compelling the display of the "danger-signal," the setting of an alarm, and the operation of a time-recorder, 35 every time the operator receives a train-order, provided the signal is not already at "danger," and the alarm set, at the time the order is received, substantially as specified and for the purpose set forth.

45 2. In safety devices for the display of train-order signals, one or more train-order tablets normally inaccessible; means compelling the display of the signal, the setting of an alarm—both locked in these positions—and the operation of a watchman's time-recorder, as the 50 only way of gaining access to the tablets; further means compelling that all the tablets be again rendered inaccessible, before the signal can be changed to "clear," or the alarm

55 unset, or another record of time made, whereby the operator is compelled to repeat the operation every time he receives an order after the signal has been set "clear," as specified and for the purpose set forth.

60 3. In safety devices for the display of train-order signals, one or more train-order tablets rendered normally inaccessible; mechanism for controlling the signal, and an alarm, and operating a time-recorder; means coöperating 65 with said mechanism, by which—in the act of gaining access to the tablets—it is locked beyond the control of the operator, in

the position displaying the signal at "danger," and setting the alarm for trains; further means compelling that all the tablets be again 70 rendered inaccessible, before the signal can be changed to "clear" and the alarm unset, as specified and for the purpose set forth.

4. In safety devices for the display of train-order signals, a case containing train-order blanks normally inaccessible therein; and mechanism compelling the display of the signal and the operation of a time-recorder as a means of gaining access to the tablets, as specified and for the purpose set forth. 80

5. In safety devices for the display of train-order signals, a case containing train-order blanks normally inaccessible therein; means compelling the display of the signal at "danger," the setting of an alarm for trains—both 85 locked in these positions—and the operation of a time-recorder, whenever the tablets are rendered accessible, as specified and for the purpose set forth.

6. In safety devices for the display of train-order signals, a receptacle having train-order blanks normally locked therein; and mechanism for controlling the signal and an alarm, and operating a time-recorder; means coöperating with said mechanism by which—in 95 the act of gaining access to the tablets—it is locked, beyond the control of the operator, in position to display the "danger-signal," and to set the alarm for trains, as specified and for the purpose set forth. 100

7. In safety devices for the display of train-order signals, a receptacle having train-order blanks normally locked therein; a door therefor; and signal-controlling means, carried by said receptacle and coöperating with said door 105 to lock and unlock the same in such a way that the act of locking and unlocking the door displays the signals, as specified and for the purpose set forth.

8. In safety devices for the display of train-order signals, a cabinet; a series of tablets normally housed and locked therein; an operating-bar forming a lock therefor and controlling the signal; and designed to be locked itself by any one, or more, of a series of locks 115 controlled by the tablets, whereby the act of locking the cabinet displays the "white" signal, that of unlocking it the "red," and that of removing a tablet from it locks the signal at "red," as specified and for the purpose set 120 forth.

9. In safety devices for the display of train-order signals, a tablet-cabinet carrying signal-operating means, and having a door co-operating with said means, whereby the signal is locked in whichever position it is caused to assume, as specified and for the purpose set forth. 125

10. In safety devices for displaying train-order signals, a cabinet, a locking-door co-operating therewith, means mechanical for locking and unlocking the door—which means also controls the signal—whereby the acts of locking and unlocking the door display the 130

signals; said door also coöperating simultaneously with said signal-operating means, to lock the signal in whichever position it is caused to assume, as specified and for the purpose set forth.

11. In safety devices for displaying train-order signals, the combination with a cabinet, of signal-controlling means, and a door adapted to coöperate with said means and cabinet to in such a way that every time the signal is set "red," the door simultaneously unlocks the cabinet and locks the signal in this position; and every time the signal is set "white," the door again by a single movement, performs the double function of locking the cabinet and locking the signal in this position, as specified and for the purpose set forth.

12. In safety devices for the display of train-order signals, the combination of a cabinet, a door having a projection or uncut-away portion, a signal-operating bar having a recess or cut-away portion, whereby the cabinet is unlocked and the bar locked whenever it is brought into position to display the "danger-signal," and also whereby the cabinet is locked and the bar is locked whenever it is brought into position to display the "white" signal, as specified and for the purpose set forth.

13. In safety devices for the display of train-order signals, a cabinet; a series of tablets normally locked therein; a locking-door therefor; means mechanical for locking and unlocking the door and displaying the signal; a series of locks controlled by said tablets and adapted to coöperate with said signal-operating means, whereby the signal is locked in the position indicating "danger" every time a tablet is removed from its place in the cabinet, as specified and for the purpose set forth.

14. In safety devices for the display of train-order signals, a cabinet having a door and a series of tablets normally locked therein by said door; a bar controlling the door and signal; a series of locks controlled by the tablets and coöperating with said bar, whereby the bar is locked in the position indicating "danger," every time a tablet is removed from the cabinet, as specified and for the purpose set forth.

15. In safety devices for the display of train-order signals, a cabinet having a door; a series of tablets normally locked therein by said door; an operating-bar controlling the door and signal; and means whereby said bar is locked every time a tablet is removed from its place in the cabinet, as specified and for the purpose set forth.

16. In safety devices for the display of train-order signals, a cabinet having a door; a series of tablets normally locked therein by said door; an operating-bar having recesses, controlling the door and signal in such a way that the movement of said bar, necessary to unlock the door, displays the "danger-signal," and brings one of the recesses of said bar into registration with the series of tablet-locks, so that one of said locks enters said recess every

time a tablet is removed from its place in the cabinet, as specified and for the purpose set forth.

17. In safety devices for the display of train-order signals, a cabinet; a locking-door therefor, in coöperation with the signal-actuating mechanism; a series of tablets normally locked therein, and controlling a series of locks also coöperating with the signal-actuating mechanism, whereby said mechanism is unlocked only when all the tablets are in the cabinet, and the door closed upon them, as specified and for the purpose set forth.

18. In safety devices for the display of train-order signals, a cabinet having signal-operating connections and a series of train-order tablets, always housed and locked therein, when the signal is set "clear," as specified and for the purpose set forth.

19. In safety devices for the display of train-order signals, a cabinet having signal-operating connections, and a series of train-order tablets normally housed therein, accessible only when the signal is set at "danger," as specified and for the purpose set forth.

20. In safety devices for the display of train-order signals, a cabinet having projecting sides provided with grooves; a door movably received by said grooves; a signal-operating bar disposed at right angles to said door, and coöperating therewith whereby the signal is displayed at "danger," and locked in that position, by the act of unlocking and opening the door, as specified and for the purpose set forth.

21. In safety devices for the display of train-order signals, a slidable door having an uncut-away portion or projection adapted to coöperate with a cut-away portion or recess of signal-operating means, whereby the door is permitted to become unlocked, as specified and for the purpose set forth.

22. In safety devices for displaying train-order signals, a cabinet, a door therefor, and a signal-operating bar in coöperation with said door and adapted to interlock therewith when the signal is set "clear," whereby the door is locked by the bar and the bar is locked by the door, as specified and for the purpose set forth.

23. In safety devices for the display of train-order signals, a door having an uncut-away portion or projection, adapted to coöperate with a cut-away portion or recess of signal-operating means, whereby the door is unlocked and the signal-operating means locked, as specified and for the purpose set forth.

24. In safety devices for displaying train-order signals, a slidable door having a recess, and within said recess an uncut-away portion or projection, as specified and for the purpose set forth.

25. In safety devices for the display of train-order signals, a door having a projection.

26. In safety devices for the display of train-order signals, a slidable door having a recess, and within said recess an uncut-away portion

or projection; said recess adapted to receive signal-operating means between its projecting portion and its opposite side, whereby said door is securely held in its locked position; 5 said projection being further designed to be received into a recess in the signal-operating means, whereby the door is permitted to move in a direction to unlock the cabinet, and by the same movement to lock the said signal-operating means, as and for the purpose set forth.

27. In safety devices for the display of train-order signals, a slidable door having a recess with an uncut-away portion or projection 15 therein, and an operating-bar received by said recess, whereby the door is held normally locked; said bar also having a recess adapted to receive the projecting portion of the door, thereby permitting the door to become un- 20 locked while it locks the operating-bar, as specified and for the purpose set forth.

28. In safety devices for the display of train-order signals, a cabinet having forwardly-extending sides provided with grooves; a door 25 movably-received into said grooves, and having an aperture provided with an uncut-away portion or projection; a signal-operating bar carried by said cabinet and normally received into said aperture between its uncut-away portion and the opposite side thereof, whereby the door is held in its locked position; said bar itself having a cut-away portion or recess adapted to receive the uncut-away portion or projection of the door, whereby the door 35 is unlocked and the signal-operating bar is locked, as specified and for the purpose set forth.

29. In safety devices for the display of train-order signals, a cabinet having a door and a 40 series of tablets normally locked therein; a series of locks controlled by the tablets; and an operating-bar coöperating with said door and series of locks in such a way that when the door is unlocked and a tablet taken from 45 the cabinet, to receive a train-order, the signal is displayed at "danger," locked in that position by both the door and tablet lock, as specified and for the purpose set forth.

30. In safety devices for the display of train-order signals, a cabinet having a door with a 50 projection, and a series of tablets normally locked therein by said door; a series of locks having projections and normally supported by said tablets; an operating-bar controlling 55 the door and signal, and adapted to coöperate with the locks in such a way that every time the bar is moved to unlock the door, the "danger signal" is displayed, and one of the recesses of said bar is brought into registration 60 with the projection of the door, which drops into it by gravity, thereby unlocking the cabinet and locking the bar, while another recess of said bar is brought into registration with the series of tablet-locks whereby one of said 65 locks is permitted to drop downwardly by gravity and engage said bar and further lock the same every time a tablet is removed from

its place in the cabinet; as and for the purpose set forth.

31. In safety devices for the display of train-order signals, a cabinet having a series of tablets normally locked therein; means for locking and unlocking the tablets and operating the signal; a series of locks controlled by said tablets and coöperating with said signal-operating means, to lock the same every time a tablet is removed from the cabinet; said series of tablet-locks being each provided with a projection having an inclined side adapted to contact with a tablet by which it is elevated and normally held out of engagement with the signal-operating means, as specified and for the purpose set forth.

32. In safety devices for the display of train-order signals, a cabinet having shelves with 85 recesses, and intervening spaces; a series of tablets carried in said intervening spaces and normally locked therein; an operating-bar controlling the door and signal; a series of tablet-locks having projections extending into 90 the recesses of the shelves, and operated by said tablets to lock the operating-bar whenever a tablet is removed from the cabinet, as specified and for the purpose set forth.

33. In safety devices for the display of train-order signals, a cabinet having shelves and intervening spaces; a series of tablets having extended base-pieces, and carried in said intervening spaces and normally locked therein; an operating-bar controlling the locking 95 mechanism therefor, and the signal; a series of locks—having projections with inclined faces extending into recesses in the shelves—elevated and normally supported out of engagement with the operating-bar by the 105 extended base-pieces of the tablets, entered beneath the inclined sides of the projections; said extended base-pieces of the tablets over-reaching the recesses in the shelves, and being supported by the walls of said recesses, 110 thereby permitting the use of comparatively light and thin material in the manufacture of said base-pieces, as specified and for the purpose set forth.

34. In safety devices for the display of train-order signals, a cabinet having a series of tablets normally locked therein, and signal-controlling mechanism, and means by which the signal is set at "danger," and is doubly locked in that position, whenever the operator has undelivered train-orders on hand; and a third independent lock, also coöperating with said signal-controlling mechanism, whereby the signal is additionally locked when set at "danger;" said independent 125 lock being controlled by some designated party, whose presence and coöperation are necessary to unlock the same whenever it is desired to change the signal, as specified and for the purpose set forth.

35. In safety devices for the display of train-order signals, a cabinet having a door and a series of tablets normally locked therein by said door; a series of locks controlled by the

tablets; an independent lock; and an operating-bar controlling the door and signal and adapted to coöperate with said door and locks in such a way that whenever the bar is moved 5 sufficiently to unlock the door, the "danger-signal" is displayed and one of the recesses of said bar is brought into registration with a projection of the door, which projection drops down into said recess by gravity, thereby locking the bar and unlocking the cabinet; while another recess of said bar is brought into registration with the series of tablet-locks, by which the bar is additionally engaged and locked, whenever one or 10 more tablets are removed from the cabinet; while at the same time a third recess of said bar is brought into registration and engagement with the independent lock, by all of which means the operating-bar is triply 15 locked, whenever the operator has undelivered train-orders on hand; said independent lock being controlled by some designated party whose presence and coöperation are necessary to unlock the same whenever it is 20 desired to change the signal, as specified and for the purpose set forth.

36. In safety devices for the display of train-order signals, a cabinet having a series of tablets normally locked therein and a signal-operating bar and means coöperating therewith, by which the signal is of necessity set at "danger," and is locked in that position, as a means of gaining access to the tablets; and means whereby the signal is additionally locked whenever one or more tablets are 30 removed from the cabinet; and a third independent lock, which also engages the operating-bar automatically whenever the signal is set in that position; said third lock being under the control of some designated party, whose presence and coöperation are necessary in order to change the signal, by all of which means the signal is triply locked at "danger" whenever the operator has undelivered 35 train-orders on hand, as and for the purpose set forth.

37. In safety devices for the display of train-order signals, a signal, and means in coöperation therewith by which a record is made of the time at which each change of the signal 40 takes place, as specified and for the purpose set forth.

38. In safety devices for the display of train-order signals, a cabinet having a series of tablets, and signal-operating mechanism, and means coöperating therewith, compelling the operation of said mechanism and through it the display of the signal at "danger," every 45 time a train-order is received after the signal has been set at "clear," and means carried by said signal-operating mechanism, adapted to coöperate with a watchman's time-recorder, whereby a record is made of the time at which each change of the signal takes place, as specified and for the purpose set forth.

39. In safety devices for the display of train-order signals, a cabinet having a series of

tablets and a signal-operating bar, and means compelling the operation of said bar in a way to display and lock the signal at "danger," 70 every time a train-order is received, provided the signal is not already set at "danger;" and means carried by said bar bringing it in coöperation with a watchman's time-recorder, whereby a record is made of the time 75 at which each operation of the signal takes place, as specified and for the purpose set forth.

40. In safety devices for the display of train-order signals, a cabinet having tablets, and signal-operating mechanism, and means compelling the operation of said mechanism in a way to display the signal at "danger" every time a train-order is received, provided it is not already in that position; means coöperating with said mechanism for recording the time at which each operation of the signal takes place; and alarm mechanism in co-operation with said signal-operating mechanism, and the railroad-track, by which an alarm 90 is sounded every time a train passes a signal set at "danger," as specified and for the purpose set forth.

41. In safety devices for the display of train-order signals, a cabinet having a signal-operating bar, and means compelling that the signal shall be locked in the position indicating "danger" whenever the operator has undelivered train-orders on hand; means coöperating with said bar for recording the time 95 at which each change of the signal takes place; and further means controlled by said bar whereby an alarm is sounded, every time a train passes the signal when set at "danger," as specified and for the purpose set forth. 100

42. In safety devices for the display of train-order signals, signal-operating mechanism, and means coöperating therewith for recording the time at which each change of the signal takes place; in combination with means 110 for sounding an alarm whenever a train passes a signal set at "danger," as specified and for the purpose set forth.

43. In safety devices for the display of train-order signals, signal-operating mechanism, 115 and means coöperating therewith for sounding an alarm, every time a train passes a signal set at "danger," and every time the signal is changed, as specified and for the purpose set forth. 120

44. In safety devices for the display of train-order signals, a receptacle having train-order blanks normally housed and locked therein; signal and alarm controlling mechanism; and means coöperating with said mechanism, 125 whereby the "danger-signal" is displayed and the alarm set for trains—and both locked in these positions, by the act of gaining access to the tablets, as specified and for the purpose set forth.

45. In safety devices for the display of train-order signals, a receptacle having a series of train-order blanks normally locked therein; in combination with signal and alarm con-

5 troling mechanism and means for setting, changing, locking, and unlocking the same in unison with each other, by the compulsory acts of gaining access to the tablets, and clearing the signal for trains, as specified and for the purpose set forth.

46. In safety devices for the display of train-order signals; in combination with an alarm-bell, a lever controlled by the signaling mechanism, and designed to be brought into co-operative relation to passing trains whenever the signal is set at "danger;" said lever being connected to the signaling mechanism by a rod which carries adjustable means of engaging the bell, and is connected to the signaling mechanism by means of a slot, whereby said rod is permitted to move freely in sounding an alarm, without disturbing the signal, as specified and for the purpose set forth.

20 47. In safety devices for the display of train-order signals, signal-operating mechanism; alarm mechanism controlled thereby, and connected therewith by means permitting the alarm mechanism to be operated independently of the signaling mechanism in sounding an alarm, as specified and for the purpose set forth.

30 48. In safety devices for the display of train-order signals, a rod and bell-lever in engagement with signal-operating mechanism, said rod capable of longitudinal movement upon said mechanism, and having means for engaging and ringing the alarm-bell when the signal is set at "danger," and when the signal 35 is changed from one position to another, as specified and for the purpose set forth.

40 49. In safety devices for the display of train-order signals, signal-operating mechanism and an alarm connected therewith, and means 45 mechanical for sounding the alarm every time the signal is changed, as specified and for the purpose set forth.

45 50. In safety devices for the display of train-order signals, a rod in slotted engagement with a signal-operating lever and carrying a bracket brought into co-operative relation to an alarm-bell when the signal is set at "danger;" said signal-lever, through said rod, also controlling an alarm-lever, one end of which 50 is brought into position to be engaged by the wheels of passing trains when the signal is set at "danger," as specified and for the purpose set forth.

55 51. In safety devices for the display of train-order signals, a signal and an operating-lever therefor; alarm mechanism controlled by said lever and terminating in an alarm-lever having one part thereof adjacent to or abutting against one of the rails of the track, and when 60 the signal is set at "danger," elevated above the track sufficiently to be depressed by the overlapping portion of the wheels of a passing train, as specified and for the purpose set forth.

65 52. In safety devices for the delivery of train-orders, an alarm-lever, one part of which is located adjacent to or in engagement with one

of the rails of a railroad-track; and means for preventing any binding or wedging between said rail and lever, and for locating the fulcrum of said lever in a plane above that occupied by the lever, whereby any binding or wedging between said rail and lever is prevented as specified.

70 53. In safety devices for the delivery of train-orders, a lever having its fulcrum located in a plane above that occupied by the lever, as specified and for the purpose set forth.

75 54. In safety devices for the display of train-order signals, a lever suspended from a point above itself, said point forming the fulcrum of the lever.

80 55. In safety devices for the display of train-order signals, a lever having an upwardly-extending projection, and its fulcrum-point located therein, and the lever suspended therefrom; whereby the strain imposed upon said upwardly-projecting portion is always a matter of tension and not of compression.

85 56. In safety devices for the display of train-order signals, an alarm-lever normally swinging against one of the rails of a railroad-track, and designed to be depressed by the wheels of a passing train; and means for moving said lever in a substantially horizontal direction 90 out of the path of said wheels.

95 57. In safety devices for the display of train-order signals, signal-operating mechanism; a bell-rod and an alarm-lever moving in unison with said mechanism, said alarm-lever normally swinging against one of the rails of a railroad-track into the path of the wheels of a passing train; and means for withdrawing said lever, in a substantially horizontal direction, out of the path of said wheels, whenever 100 the signal is set at clear.

105 58. In safety devices for the delivery of train-orders, an alarm-lever having one part designed to abut against a rail and to be depressed, and having an upwardly-extending 110 portion containing the fulcrum-point, whereby the end of the lever abutting against the rail, swings from it when depressed, as specified and for the purpose set forth.

115 59. In safety devices for delivering train-orders, signal-operating mechanism and means mechanical co-operating therewith to sound an alarm every time the signal is changed, whereby the operator is notified that the signal mechanism is in working order, as specified and for the purpose set forth.

120 60. In safety devices for delivering train-orders, an alarm-lever adapted to be depressed, and a bell-rod in direct connection therewith; a bracket secured to said rod to contact with 125 an alarm-bell; said rod being designed to be thrown or tossed by said lever in a direction to sound an alarm whenever the lever is suddenly depressed, as specified and for the purpose set forth.

130 61. In safety devices for delivering train-orders, an alarm-lever in co-operative relation to the wheels of a passing train; a bell-rod in connection therewith, designed to be thrown

or tossed a greater distance by the sudden depression of said lever, than it would be elevated by a gentle depression thereof to the level of the rail; and a bracket carried by 5 said rod for engaging an alarm-bell, when said rod is elevated to its highest limit, whereby the alarm will be sounded by a train passing rapidly, but will not be sounded by one moving slowly, as specified and for the purpose set forth.

62. In alarms coöperating with train-order signals, a counterbalanced lever adapted to be depressed by the wheels of a passing train; a rod carried by the signaling mechanism 15 and designed to move freely thereon longitudinally, having two nuts or stops between which it is loosely received by a slot in said lever; said nuts being sufficiently separated from each other to permit the bell-rod to move 20 upwardly, by the momentum of a sudden depression a greater distance than it would be elevated by a gentle depression of said lever to the level of the rail, as specified and for the purpose set forth.

63. In safety devices for the display of train-order signals, the combination with signaling mechanism, and alarm mechanism operated thereby and in unison therewith to sound an alarm every time the signal is changed; of an 25

alarm-lever adapted to be depressed by the 30 wheels of a passing train, to operate the alarm mechanism independently of the signaling mechanism; and means of adjusting said alarm mechanism at will, to prevent the sounding of the alarm when the signal is 35 changed, or when the lever is gently depressed, and to cause an alarm only when the lever is suddenly and violently depressed, whereby an alarm may be sounded only by a rapidly-passing train, as specified and for 40 the purpose set forth.

64. In safety devices for the display of train-order signals, a pivoted signal-operating lever; a bell-rod having slotted engagement therewith; and means for tossing said rod vertically to sound an alarm; the pivot-point of said lever and the point of engagement with said rod being in a line parallel to the travel of said rod; whereby no strain can be imposed upon the signaling mechanism, nor any 45 motion imparted thereto by the vertical motion 50 imparted thereto by the vertical thrust of said rod.

In testimony whereof I affix my signature in presence of two witnesses.

EDWIN E. OVERHOLT.
